UNITED STATES PATENT OFFICE.

ALBERT F. STONE, OF MONTCLAIR, NEW JERSEY.

CARTON-CASE FOR COLLAPSIBLE TUBES.

1,252,051.

Specification of Letters Patent.

Patented Jan. 1, 1918.

Application filed January 8, 1915, Serial No. 1,123. Renewed May 25, 1917. Serial No. 170,986.

To all whom it may concern:

Be it known that I, ALBERT F. STONE, a citizen of the United States, residing at Montclair, in the county of Essex and State 5 of New Jersey, have invented certain new and useful Improvements in Carton-Cases for Collapsible Tubes, of which the following is a specification.

This invention relates to collapsible cartons 10 or casings forming an outer covering for collapsible tubes containing pastes, creams and other semi-liquid or liquid contents adapted to be expelled by squeezing the tube.

15 The object of my invention is to provide a casing or carton, which may be made of cardboard or other suitable material, and which incloses the collapsible tube, permitting the continued use of the tube contents 20 while preserving the shape and contour of the carton or cover.

The cover is preferably constructed of a single blank of sheet material, cut into the shape substantially as shown, and adapted 25 to be folded on the lines indicated.

In the accompanying drawings forming a part of the specification, Figure 1 is a plan view of the blank showing the outline and the crease lines upon which it is folded; Fig. 30 2, is a perspective view showing the carton partly folded and the manner of placing the collapsible tube in position therein; Fig. 3, is a perspective view showing the carton folded but with the top member swung back to 35 expose the side flaps; Fig. 4, is a perspective view of the folded carton with the bottom clamp ready to be secured; Fig. 5, is a perspective of the carton with an inclosed tube, and partly broken away to show how 40 the contents of the tube are expelled by pressing the carton between the fingers; Fig. 6, is a plan view of a blank partly broken away, showing a slightly modified carton construction; Fig. 7, is a detail view of the 45 bottom end of the latter form; Fig. 8, is a sectional view on the line 8—8 of Fig. 5, and Fig. 9, is a cross-section on the line 9—9 of Fig. 7.

The carton blank is cut preferably from 50 card-board or fiber-board and creased in the manner illustrated in Fig. 1, and comprises top and bottom 2, and 4, respectively, end 3, with its flaps 3^a, 3^b, and sides 6 and 7 with their flaps 6^a and 7^a. The top and bottom 55 members, 2 and 4, constituting the face members of the wedge, and the end member 3,

forming the base of the wedge, are rectangular, while the sides are triangular, so that the folded carton is wedge-shape. The lines a, b, and c, d, are lines of fold between the 60 sides and the flaps while the lines a, e, and c, f, are crease lines extending longitudinally upon a median line through the sides and formed in the blank. The end flaps 3^a, 3^b are also creased on a median line as 65 indicated in broken lines. The end or base member 3 is provided with a central aperture 9 through which the neck of the collapsible tube may protrude.

When it is desired to incase the collapsible 70 tube in the carton, the end or base member 3, is bent up perpendicular to the bottom face member 4, and the tube 10, is placed in position as indicated in Fig. 2, with the neck protruding through the aperture 9. The end 75 flaps are then bent inwardly and the sides and their flaps are folded over in the manner indicated in Fig. 3; after which the top face member 2 is folded down over the side flaps, thereby forming the wedge-shape casing 80 shown in Fig. 4. A suitable metal clip 12, may be placed over the apex end and fastened by a sealing machine to clamp the parts together. The edges a, g, and c, b, of the side flaps may be cut substantially 85 square, as shown in Figs. 1, 2 and 3, so that they will extend under the clamps 12 and be permanently secured thereby as shown in Fig. 8, or they may be cut away at an angle along the lines a, g' and c, h', as indicated in 90 Figs. 6 and 7, so that the flaps will be free from the clamps as indicated in Fig. 9. In the latter case, the clamps 12 will only fasten together the top and bottom or face members 2 and 4 of the wedge, as shown in 95 Fig. 7, and the side flaps may be folded over and inserted afterward if preferred and the sides 6 and 7 being thus free, may be opened out at any time to expose the tube as indicated in Fig. 7.

As previously stated, the neck 14 of the tube protrudes through the aperture in the end member, as shown in Fig. 5, so that the cap 15 may be removed and the contents 100 expelled, as at 16, by pressure of the fingers 105 upon the carton in the manner indicated in Fig. 5. In said figure the carton is broken away to show how the tube within is squeezed by the pressure upon the carton. The sides of the carton yield under pressure 110 and bow or bulge outwardly along the crease lines a, e and c, d, this result being

the function of these crease lines. The end or base 3, however, is uncreased so that it maintains its shape due to the rigidity of the card-board. When the contents of the 5 tube have been nearly all expelled, so that it is necessary to press the carton near the larger end, the end flaps 3^a, 3^b, also bulge or bow outwardly along the crease lines with the sides.

10 The advantages to be derived from the use of my invention will be appreciated from the above description. The carton maintains its original shape, due to the stiffness or rigidity of the card-board or fiber-board, 15 and yet permits the contents of the tube to be expelled in the usual manner by progressively pressing from the closed end toward the discharge end or neck on account of the crease lines in the edge members 7. The 20 neat appearance of the package is, therefore, preserved during the entire period of use and the unsightly appearance of the wrinkled and distorted partly collapsed tube is concealed. The faces of the carton may 25 receive printed matter such as advertisements and labels describing the contents and directions for its use, making it unnecessary to place the same upon the tube and these matters are preserved intact throughout 30 the use of the contents, which is an important advantage. The surface of the carton may also be varnished or otherwise made durable and water-proof.

35 While I have described in detail the particular construction illustrated in the accompanying drawings for the purpose of disclosing an embodiment of my invention, I am aware that various changes may be made therein within the scope of the appended 40 claims and without departing from the spirit of my invention.

I claim:—

45 1. A carton casing or cover for collapsible tubes, comprising a fiber-board blank folded into a wedge-shaped box and having its edge members provided with longitudinal crease lines upon which said members may fold when pressure is exerted upon the faces of the wedge, while its end or base member 50 maintains its shape due to its stiffness or rigidity.

2. A carton casing or cover for collapsible

tubes, comprising a fiber-board blank folded into a wedge-shaped box and having side, edge and base members, said edge members 55 being provided with longitudinal crease lines upon which they may fold when pressure is exerted upon the faces of the wedge, the rigidity of the base member maintaining its shape and being provided with an 60 aperture to receive the neck of a collapsible tube.

3. A carton casing or cover for collapsible tubes, comprising a fiber board blank foldable into a wedge-shaped box, said blank having rectangular portions adapted to form the opposite face members of the wedge, an intermediate portion having an aperture to receive the neck of a collapsible tube and connected by folding joints with said rectangular portions, and triangular portions having outer marginal flaps and united at their inner longitudinal edges by folding joints with the opposite edges of one of said rectangular portions, said intermediate portion being sufficiently rigid to prevent distortion when the triangular portions are collapsed by pressure on the face members. 70

4. A carton casing or cover for collapsible tubes, comprising a blank foldable into a 80 wedge-shaped box, said blank having rectangular portions adapted to form the opposite face members of the wedge, an intermediate rectangular portion having an aperture to receive the neck of a collapsible 85 tube and connected by folding joints upon opposite sides with said rectangular portions and having flaps united to the other opposite sides, and triangular portions having outer marginal flaps and united at their 90 inner longitudinal edges by folding joints with the opposite edges of one of said rectangular portions, said triangular portions having longitudinal crease lines causing the triangular portions to bulge outwardly when 95 pressure is applied to the outer margins thereof.

In testimony whereof I affix my signature in presence of two witnesses.

ALBERT F. STONE.
